UNITED STATES PATENT OFFICE

RHODA B. BURGGRAEF, OF KANSAS CITY, MISSOURI

SIGNALING DEVICE

Application filed February 17, 1930. Serial No. 429,173.

This invention relates to new and useful improvements in signaling devices, and particularly to signaling devices used on vehicles, to advise drivers of other vehicles of an intention to change direction.

One object of the invention is to provide a signaling device which is of simple construction, and which is easy and effective in its operation.

Another object is to provide a device of this character wherein a greater display of signal arm surface is possible than in similar devices heretofore.

Another object is to provide a device of this character which can be easily and quickly taken apart and assembled.

Other objects and advantages will be apparent from the following description when taken in connection with the accompanying drawings.

In the drawings:

Figure 1 is a front elevation of the device in applied position on an automobile, the signal arm being in inoperative position.

Figure 2 is a top plan view of the device.

Figure 3 is a vertical sectional view on line 3—3 of Figure 2.

Figure 4 is a side elevation of the signal arm containing casing.

Figure 5 is a vertical sectional view on the line 5—5 of Figure 2.

Figure 6 is a transverse sectional view on the line 6—6 of Figure 3.

Figure 7 is a transverse sectional view on the line 7—7 of Figure 3.

Referring particularly to the accompanying drawings, 10 represents a portion of the body of an automobile, and 11 a portion of the instrument board, in connection with the present invention is especially adapted for use.

Disposed vertically against the left side of the body of the automobile, and adjacent of the driver's door thereof, is an elongated casing 12, having a vertical longitudinal slot 13

in its outer side edge, and the vertical open-ended slots 14, in the upper portions of its side walls. Disposed transversely through the casing, with its ends resting in the lower ends of the slots 14, is a shaft 15, and secured on said shaft, within the housing, is the depending signal arm 16, which is a representation of a human arm, with a hand on its outer end. It will be particularly noted that the shaft is eccentrically mounted within the inner end of the arm 16, for a purpose which will presently appear herein. Pivots connected to the forward wall of the housing, adjacent the lower end, and adjacent the inner or attached side wall, is an upwardly extending lever 17, and pivotally connected to the upper end of this lever is a short link 18, which has its other end pivotally connected with the intermediate portion of the upper end of the signal arm 16. A cap 19 closes the upper end of the housing, and has its depending flanges 20 disposed within the said end of the housing, such flanges being provided with openings 21, and having metal strips 22 secured to their inner faces, which strips all have openings registering with the openings 23, for the reception of the ends of the said shaft 15. Screws 24 are provided for securing the cap in place. Upon removal of the screws 24, the cap, together with the signal arm, may be conveniently lifted from the casing.

In the intermediate portion of the attached side wall of the casing there is formed an opening in which is secured the bushing 25, and slidably in this bushing is one end of a rod 26, said rod extending into the casing and being pivotally connected with the lever 17, by means of the pin 27, said pin being disposed through a longitudinal slot 28, in the lever 17, to compensate for the arcuate movement of the arm 16, when swung on its pivot.

Properly secured to the lower edge of the instrument board 11, by means of the clamp

29, is a member 30, which has a longitudinal slot 31, in its front portion, the upper wall of said slot being formed with a plurality of ratchet teeth 32, as clearly seen in Figure 1. 5 A pivot 33 is carried by the inner portion of the member 30, and mounted on this pivot is a horizontally movable lever 34. The outer end of the lever 34 is provided with a handle 35, and is adapted to be engaged in any one 10 of the ratchet teeth 32, while the inner end of the lever is pivotally connected with a rod 36, which has its other end connected with the before-mentioned rod 26, by means of the turnbuckle 37, by means of which adjustment of the throw of the rod may be made. 15

Fixed on the forward end of the shaft 15, outside of the casing 12, is a plate 38, which rotates with the shaft and signal arm, and serves to give the appearance of the arm being pivotally mounted on the outside of the casing. 20

The operation of the device may be briefly described as follows:

Normally the arm 16 lies within the casing 12, and when the driver desires to signal a change of direction, he grasps the handle of the lever 34, depresses the lever to a slight degree, to disengage it from the ratchet teeth, and then swings the lever toward the right. 25

30 When the lever is below the ratchet tooth 32, which corresponds to the position the signal arm 16 is to assume, the operator lifts the lever so that it engages with said tooth. This swinging movement of the lever 34 exerts 35 a pushing action on the rods 26 and 36, with the result that the lever 17 is swung toward the outside of the casing 12, whereupon the link 18 will cause the signal arm 16 to swing upwardly into the position indicative of the direction in which the automobile is to go. 40 An outward downward inclined position of the arm indicates a left turn; a horizontal position indicates a stop; while an upward outward inclined position indicates a right turn. Placing the lever 34 in any one of the 45 teeth 32 will produce a corresponding movement and positioning of the signal arm. 105

Ordinarily only that part of the arm 16, which projects beyond the side of the casing, 50 would be seen, and to produce the effect that the entire arm is pivotally mounted on the front of the casing, and that the observer sees the entire arm, the plate 38 is provided, to move with the shaft 15, and the said arm, 55 such plate being of the same color as that of the arm. 110

What is claimed is:

1. A direction signal for a vehicle comprising a casing, a signal arm mounted in the 60 casing for movement into and out of the casing, and means outside of the casing and movable with the arm for lending the appearance of a continuation of the arm. 120

2. A direction signal for a vehicle comprising a casing, a signal arm pivotally 65

mounted in the casing for movement into and out thereof, a lever pivotally mounted in the lower portion of the casing, a link connected with the upper end of the lever and connected eccentrically at its upper end with the pivoted end of said arm, and a rod connected with the lever intermediate its pivotal mounting and its connection with said link, for moving the lever whereby to swing the arm. 70

In testimony whereof, I affix my signature. 75
RHODA B. BURGGRAF.
